TROUSERS HANGER

Hugo F. Saenger, Milwaukee, Wis.

Application July 9, 1937, Serial No. 152,832

2 Claims. (Cl. 223—96)

The present invention relates to trousers hangers and has for its prime object to provide a simple, inexpensive, and efficient hanger adapted to engage and support the trousers by their cuffs whereby the trousers will be held in a natural position and will retain their crease.

Another important object of the invention resides in the provision of a hanger of this nature which is extremely simple in construction, adapted to take care of a plurality of trousers, easy to manipulate, inexpensive to manufacture, strong and durable and otherwise well adapted for the purpose for which it is designed.

With the above and numerous other objects in view as will appear as the description proceeds, the invention consists in certain novel features of construction, and in the combination and arrangement of parts as will hereinafter be more fully described and claimed.

20 In the drawings:—

Figure 1 is a side elevational view of a hanger embodying the features of my invention.

Figure 2 is an end elevation thereof.

Figure 3 is a top plan view thereof.

25 Figure 4 is a perspective view of one of the arms.

Figure 5 is a perspective view of the clamp members.

Figure 6 is a perspective view of the hook.

30 Referring to the drawings in detail it will be seen that there are a pair of elongated arcuated clamp plates or bars 5 the centers of which are riveted or otherwise secured as at 6 to arms 7. These arms are provided with side flanges 8 and

35 9 the latter of which overlap the former and the flange portions at their ends which overlap are rockable on a pin portion 25 of a hook member to be presently described.

A bail of U-shaped construction includes a 40 straight bight 12, arms 14, and pintles 15. The bight 12 is adapted to engage with protrusions 17 formed on one arm 7 and the pin 10 with protrusions 17' on the other arm.

The bail engages the arms and with the lever 45 element 20 engages the pin 10 and the bight portion 12 with the protrusions 17 and 17' respectively and can be cammed to clamp the elements 5 with the trousers or other garment as may be desired.

In this connection it is to be noted that the flanges 8 swing on the portion 25 of a hook 27, said hook being formed of a single strand of wire bent upon itself intermediate its ends to provide a double strand 26, one end of the wire being formed with an eye 30 and the other end of the wire being bent angularly to form the pin 25 which is inserted through openings 11 in the inner ends of the flanges 8 and 9 and also through the eye 30.

10 It is thought that the construction, operation, utility and advantages of this invention will now be quite apparent to those skilled in this art without a more detailed description thereof.

The present embodiment of the invention has 15 been described in considerable detail merely for the purposes of exemplification since in actual practice it attains the features of advantage enumerated as desirable in the statement of the invention and the above description.

20 Having described the invention what is claimed as new is:—

1. A device of the class described comprising a pair of pivoted jaws on a garment hanger and means detachable from the jaws for clamping 25 the jaws together, said means comprising spaced abutments on the jaws, a U-shaped bail enclosing the jaws, a cam lever pivoted to the free end of the bail and including spaced parallel cam lobes straddling one of the jaws and a pin extending between said cam lobes and selectively engageable with the abutments to retain the clamp in adjusted position on the jaws, the jaws including trousers engaging means.

2. A device of the class described comprising a 35 pair of pivoted jaws having spaced pivoted ends on a garment hanger and means detachable from the jaws for clamping the jaws together, the jaws including trousers engaging means, the trousers engaging means being of an arcuate formation, 40 said hanger being in the form of a wire element of one piece bent upon itself intermediate its ends to provide a hook, one end of the wire terminating in a straight bar on which the jaws are pivoted and an eye formed on the other end of the wire 45 engaging the bar between the pivoted ends of the jaws.

HUGO F. SAENGER.
